UNITED STATES PATENT OFFICE.

FERNANDO J. LE BEAU, OF NILES CENTER, ILLINOIS, ASSIGNOR OF ONE-THIRD TO ERICK BLAINE THELIN AND ONE-THIRD TO TITUS L. THELIN, BOTH OF CHICAGO, ILLINOIS.

STEPLADDER BRACE.

Application filed February 18, 1924. Serial No. 693,465.

To all whom it may concern:

Be it known that I, FERNANDO J. LE BEAU, a citizen of the United States, residing at Niles Center, in the county of Cook and 5 State of Illinois, have invented a certain new and useful Improvement in Stepladder Braces, of which the following is a specification.

This invention relates to metallic step-ladders, and particularly the diagonal brace member against which the ladder proper rests and is supported when the ladder is extended for use.

The object of the invention is to provide 15 a novel means for connecting the two separate spaced uprights ordinarily constituting the brace member referred to in such a manner that the complete brace will be very strong and rigid yet light and therefore inexpensive in construction.

The invention consists in means for attaining the foregoing and other objects; which can be easily and cheaply made; which is satisfactory in use and not readily 25 liable to get out of order; and in special features and details which will be hereafter more fully set forth in the specification and claims.

Referring to the drawings in which like 30 numerals designate the same parts throughout the several views:

Figure 1 is a side elevation, a certain part of the brace being broken away, illustrating this invention in its preferred form.

Figure 2 is a side view, taken from the right of Figure 1, showing particularly the brace of this invention.

Figure 3 is a detail plan view taken on the irregular line 3—3 of Figure 1.

Figure 4 is a perspective view showing the connection of the cross member to one upright of the brace and illustrating this invention in detail.

Figure 5 is an enlarged detail view of the 45 connection of a cross-member to the brace upright which appears in the right hand half of Figure 1 and just below the line 3.

The metal ladder to which this invention is applied as shown in the drawings consists of a conventional ladder upright 10, having steps 12 and carrying at its top parallel horizontal cross-members 14 to each of which is pivoted at 16 a generally ver-

tical brace member 18, preferably but not necessarily attached by collapsible link 55 mechanism 20 to the opposite portion of the ladder proper 10 of the device.

The problem solved by this invention is to rightly connect the two separated brace legs or rails 18 at a point intermediate the 60 hinge 16 and the ground 22 so that the complete brace mechanism will operate as a single unit swinging about the aligned hinge pivots 16.

In the preferred form of construction, the 65 desired result is attained by making the upright brace members 18 of the same style of Z bar so placed that flanges 24 thereof project toward each other and lie in the same inclined plane across the ladder, while 70 the oppositely projecting flanges 26 thereof lie in a common plane parallel to the plane of the flanges 24 and by providing a cross-bar 30 of exactly the same Z-shaped cross-section as the uprights 18 placed as shown 75 in the drawings with each of its ends 32 resting against the web of an adjacent upright brace 18, while its flange 24a rests against and is preferably welded or riveted to the corresponding flange 24 of the upright. 80 This construction and assemblage of parts so locates the flange 26a of the cross-member 30 that a solid cross-bar 34 may be passed inside said flange 26a and outside the flange 26 of the uprights 18, the end portion 85 34a of the bar which touches the flanges 26 being riveted or welded thereto.

The result of this construction is that in 90 making a ladder of this kind, it is only necessary to keep in stock one size of Z-bar to produce brace mechanisms 18—30, thereby doing away with the expense and annoyance of stocking up with two different forms of metal members to be used in making this brace mechanism. Wholly apart 95 from this convenience, the two Z-bars, one vertical and one horizontal, fit together and co-operate better with less cutting and forming than any other shapes which are available on the market. By actual experience, the construction described materially reduces the cost of this brace device.

Both Z-bars have narrow border flanges 40 which in the case of bar 30 are more or less important in retaining the parts in the 105 position of Fig. 5.

Having thus described my invention, what I claim as new and desire to secure by Letters Patent is:

1. In a device of the class described, a brace mechanism including two upright Z-members having flanges turned toward each other lying in a common plane, and two other flanges turned away from each other, lying in a different common plane;
- 5 a Z-bar cross-connection between the uprights having its ends abutting the webs of the uprights and one flange resting upon and secured to the first mentioned flanges of the uprights and a bar under the second flange of the cross-member and over the second flanges of the uprights rigidly secured thereto, for the purposes set forth.

2. A ladder construction comprising side bars of sheet metal bent into substantially Z-form, each arranged to provide an inwardly extending flange at one edge and an outwardly extending flange at the other edge; and cross members between said bars, each of said cross members being formed of sheet metal bent into substantially Z-form, one leg of said cross member being secured to said inwardly extending flanges and the other leg being provided with a reinforcing bar extending laterally and secured to the outwardly extending flanges on the side bars; substantially as described.

In witness whereof, I have hereunto subscribed my name.

FERNANDO J. LE BEAU.
